RAYMOND H. OLLEY, OF SYRACUSE, NEW YORK, ASSIGNOR TO CROUSE-HINDS COMPANY, OF SYRACUSE, NEW YORK, A CORPORATION OF NEW YORK.

UNITARY CONDUIT AND SWITCH SUPPORT FOR GASOLINE-SERVING STATIONS.

Application filed December 4, 1923. Serial No. 678,550.

This invention has for its object a combined or unitary conduit and switch support, and means for controlling the opening of the valve in the conduit and at the same time operating the switch.

The invention consists in the novel features and in the combinations and constructions hereinafter set forth and claimed.

This unitary structure is particularly designed to be used in gasoline serving or dispensing stations, where the gasoline is pumped from a storage tank into a measuring tank, the pump being driven by an electric motor which is controlled by a switch, and gasoline flowing from the measuring tank through a hose into the gasoline tank of motor vehicles.

In describing this invention reference is had to the accompanying drawings in which like characters designate corresponding parts in all the views.

Figures 1 and 2 are respectively an elevation and a plan view of this unitary structure.

Figure 3 is a sectional view taken approximately on line 3—3, Fig. 1.

This unitary structure comprises a conduit having a valve including a casing, connected therein, a switch support or housing, the housing and the conduit being joined together as a unit, and operating means for the valve and the switch including a handle member common to both operating means. In this embodiment of my invention there is an operating member for the valve, and an operating member for the switch in the switch housing, and one of said members is arranged in the path of the other, and the latter has a handle, so that, the switch is operated to close the circuit therethrough, and start the electric motor which actuates the pump, during the same operation that the valve is operated, to open the conduit to permit the gasoline to be pumped through the valve casing to the measuring tank.

As the construction of the motor controlled by the switch and the construction of the pump forms no part of this invention, further illustration and description is thought to be unnecessary and also as the construction of gasoline dispensing stations including electrically driven pumps and measuring tanks are well known, illustration and description is thought to be unnecessary, it is

sufficient to bear in mind that the switch controls the actuation of the motor which pumps the gasoline through the pipe.

1 designates the pipe or conduit, having a valve 1^a including a valve casing 2 therein, the valve being operated to open and close by a suitable stem of shaft 3 movable about an axis, usually an upright axis. The valve member or gate 1^a may be of any suitable form size and construction. 4 is the switch box or housing enclosing a switch 5 of any suitable construction, the box 4 and the conduit 1 being rigidly secured together as a unit. As here illustrated the conduit is formed with lugs 6 arranged to lap one side of the box 4, and secured thereto by screws as 7, which thread into holes in one side of the box.

The switch box has a detachable cover 8 secured thereto, in any suitable manner, as by screws 9, which cover carries switch operating means, as an endwisely movable rod 10, slidable in the cover 8, it being slidable vertically in this embodiment of my invention. The rod coacts with an actuating part or arms 11 which throws the switch, the rod being thrust in one direction to throw the switch off, by a spring 12. The spring encircles the rod and thrusts at one end against the cover, and at its other end against a shoulder or collar 13 on the rod. This shoulder 13 together with a similar shoulder 14 on the rod forms a groove which receives the ends of the actuator arm 11 of the switch.

Movement of the rod 10 upwardly against the action of the spring throws the switch to "on" position, so that, the motor is connected in the circuit, and movement of the rod in the other direction throws the switch "off" to disengage the motor.

A suitable lever is connected to the rod 10 to actuate it, that here shown, being an angular lever 15, having a hub 16 mounted on the shaft 17 supported in horizontal position on the top of the box 4, the shaft being supported in suitable lugs 18 on the side top wall of the lever. One arm of the lever has a fork 19, working in a groove formed in a collar 20 on the upper end of the rod 10, and the other arm 21 extends upwardly.

The stem 3 of the valve 1^a within the casing 2, is operated by a lever 22 mounted on said stem 3 to rock said stem about a vertical axis, one of the levers 15 and 22 being arranged in

the path of the other and the latter having a handle, by means of which it is operated, so that, when it is operated it will engage the former lever and actuate the former member, 5 and hence, the valve will be opened and the switch closed in the same operation.

As here shown, the lever 22 is provided with a suitable handle 23 and the upwardly extending arm 21 of the switch operating lever 15 extends into the path of the lever 22, such arm being provided with an engaging end as a ball 24.

When it is desired to open the valve for the purpose of pumping gasoline from the storage tank to the measuring tank, the lever 22, 15 is moved to the left, Fig. 3, or upwardly in Fig. 2, thus opening the valve and during such movement the lever 22 engages the ball 24 of the switch operating lever arm 21, and 20 causes the lever 15 to pull upwardly on the rod 10, and throw the switch "on", against the action of the spring 12. The operator holds the lever 22 to the left until he sees that the measuring tank is full or filled to the desired 25 extent and then upon releasing the handle 23 or upon turning the handle 23 to the right to close the valve, the spring 12, automatical-

ly throws the switch to "off" position, and returns the lever 15 to its normal position.

This unitary structure and the arrangement of the operating levers is particularly advantageous in that they can be readily installed as a unit in the pump system or the frame supporting the measuring tank.

What I claim is:

In a device of the class described, the combination of a conduit, a valve including a valve casing in the conduit, a switch housing mounted on the conduit and arranged at one side thereof so that the conduit is a bypass around the housing, valve operating means carried by the valve casing, a switch, a cover for the switch housing carried by the switch housing, switch operating means carried by the cover and including a portion located in the cover and removable as a unit therewith, each of said operating means including a part, one of which extends into the path of the other to be operated thereby.

In testimony whereof, I have hereunto signed my name, at Syracuse, in the county of Onondaga, and State of New York, this 15th day of November, 1923.

RAYMOND H. OLLEY.
